[57] CLAIM

The ornamental design for a barbecue attachment grid for cooking seafood, as shown and described.

DESCRIPTION

FIG. 1 is a top plan view of barbecue attachment grid for cooking seafood showing my new design;

FIG. 2 is a right side elevational view thereof, the left side being a mirror image;

FIG. 3 is a front elevational view thereof;

FIG. 4 is a rear elevational view thereof; and

FIG. 5 is a bottom plan view thereof.
The grid pattern schematically shown is continuous throughout.
